MULTIFLUID HEAT EXCHANGE PASSAGE
CONSTRUCTION

Sven Holm and Per Hilmer Karlsson, Wellsville,
N. Y., assignors to The Air Preheater Corpora-
tion, New York, N. Y.

Application April 16, 1947, Serial No. 741,878

2 Claims. (Cl. 257—246)

1

The present invention relates to heat exchange apparatus and particularly to apparatus in which heat is transferred between several streams of fluid and wherein two fluids flowing through contiguous passages in heat transfer relationship are periodically switched so that each fluid flows for a time through a passage previously traversed by the other.

In an application filed in our names on November 3, 1944, under Serial No. 561,766 we disclosed multi-fluid heat exchangers of the plate type through the passages of which one fluid is circulated to be cooled by indirect contact with two other fluids. One use contemplated for the apparatus is to cool air to very low temperatures using oxygen and nitrogen both at temperatures substantially below 0° F. The air entering at a temperature around 100° F. carries a certain amount of water vapor which sublimes to ice at low temperatures. To dispose of the ice it is necessary to periodically transpose the air and nitrogen streams so that the nitrogen re-evaporates the ice deposited from the air. The apparatus, therefore, works in two cycles, each of which must give the same performance as to heat exchange between the nitrogen and air and a uniform pressure drop must be maintained in the passages for these gases. The oxygen enters the apparatus at a lower temperature than the nitrogen but is required to leave at the same temperature and, therefore, receives heat from both the air and the nitrogen.

A feature of the invention is a heat exchanger construction in which two of the streams of fluid may be switched or transposed with respect to their relation to each other while maintaining the rate of heat transfer between nitrogen and air and without changing the pressure drop through the exchanger for any fluid.

The invention will be best understood upon consideration of the following detailed description of illustrative embodiments thereof when considered in conjunction with the accompanying drawings in which:

Figure 1 is a vertical sectional elevation of a heat exchanger embodying the invention in apparatus having a series of concentric annular passages;

Figure 2 is a transverse sectional view of a heat exchanger having two groups of passages in place of the single group in Figure 1 illustrating the connection of inlet and outlet ducts with the passages of the exchanger.

Figure 3 is an enlarged sectional view on line 3—3 in Figure 1, illustrating contiguous passages

for the flow of two fluids with extended surface in the form of fins internal with their common intermediate wall arranged to maintain the same heat transfer relationships when either fluid is switched to flow through the passage for the other;

Figure 4 is a further enlarged view of fragmentary portions of two of the contiguous fluid passages;

10 Figure 5 is a diagrammatic view of a heat exchanger embodying the invention and showing the relation of its inlet and outlet connections to the supply and discharge ducts for the various fluids.

15 In Figure 1 the four concentric wall members 11, 12, 13 and 14 define a pair of adjacent annular passages 15, 16 extending from end to end of the apparatus outwardly of a channel 17. Additional groups of passages may be provided to increase the capacity of the apparatus as illustrated in Fig. 2 showing two groups each made up of three concentric passages and Fig. 3 showing three groups. One of the cooling fluids (oxygen) enters the channels 17 through an inlet connection 19 at one end of the apparatus and is discharged from the opposite end of the exchanger through an outlet connection 20.

At the upper end of the apparatus air to be cooled enters on the left hand side through an inlet connection 21 which communicates with the outermost annular passage 15 and by a sleeve 22 penetrating the second and third annuli with the fourth annulus 15A and every third annulus thereafter, as the seventh in Fig. 3. At the lower end of the apparatus the outlet connection 24 for air communicates in like manner with the lower ends of the first, fourth and seventh annuli 15, 15A, 15B etc.

The cold nitrogen enters the bottom of the apparatus at the left hand side through an inlet connection 30 which extends toward the center of the apparatus and pierces the oxygen and air annuli 15, 17 where necessary but communicates only with the second, fifth and eighth, i. e. annuli 16, 16A, 16B, every third annulus counting from the second. At the upper right hand side of the apparatus the nitrogen is discharged through a similarly connected outlet 31 which communicates only with the upper ends of the annuli 16,

45 50 16A, 16B.

With connections so arranged the air flows countercurrent with respect both to nitrogen and oxygen, which is the desired relationship for maximum heat transfer. As shown each of the passages 15, 16 is annular but these annuli could be

subdivided, if desired, as disclosed in the parent application. As described herein, the central space 18 beyond the innermost annulus is not utilized as a heat exchange passage.

Fundamentally the apparatus comprises a plurality of adjacent parallel fluid passages. In the form described these are in groups of three concentric annuli. It may be noted that if no special provisions were made and the air were to flow in the entire outer annulus 15 in cycle I and then in the intermediate annulus 16 in cycle II, it is evident that the air would be cooled to a much lower temperature in cycle II, where it would flow between the cold oxygen in channel 17 and the cold nitrogen in passage 15. The discrepancies in the diameters of the annuli could also result in a difference in pressure drop due to difference in mass velocity. In switching the fluids in the inner groups of annulae the air would be in channels 16A and 16B in cycle II with cool nitrogen in channels 15A, 15B and cool oxygen in channels 17, 17A so that the air would remain between relatively cooler fluids; but the heat exchange conditions between air and nitrogen would not be the same in both cycles because of the different areas and gas swept wall surfaces in the sets of annular passages.

In accordance with the invention the air and nitrogen streams flow in contiguous passages (shown as annular) whose heat transfer relationships and the total flow area for each of the two gases is the same in both cycles so that the apparatus is balanced as to heat exchange relationship between air and nitrogen in the two cycles. This is so because the relations that exist between an air passage 15 and a nitrogen passage 16 in one cycle have their counterparts in the second cycle as between a passage 16 used for air and a passage 15 used for nitrogen, as a result of constructing the apparatus so that the hydraulic diameters of contiguous passages as 15, 16 and 15A, 16A are the same despite differences in diameter due to their concentricity. Heat is also exchanged at the same rate between these two gases in either cycle.

The air and nitrogen flow through the apparatus in substantially greater amount than the oxygen; therefore, extended surfaces in the form of fins 41, 42, 41A, 42A, 41B, and 42B; project from the walls 12, 12A and 12B between annulae 15, 16, 15A, 16A, 15B, 16B into the passages for these gases. The hydraulic diameter of the channels between fins must be the same for air as for nitrogen because the pressure drop increases inversely as the hydraulic diameter. For pressure drop, the hydraulic diameter (also called equivalent diameter) is defined as equal to four times the area of channel divided by the circumference. In heat transfer the hydraulic diameter of a passage depends on what portion of its perimeter is effective as heat transfer surface, and is defined as four times the cross-sectional area divided by the portion of perimeter through which heat exchange takes place. The walls 11 and 12, 12 and 13, 14 and 12A and 13A etc. are therefore spaced radially at such distances that the hydraulic diameters of any two contiguous annuli for air and nitrogen such as 15, 16 or 15A, 16A etc. (Fig. 2) are the same. This applies also to Fig. 3 wherein the passages 16A and 16B are made of greater radial width than passages 15A and 15B to obtain the same area for flow in the contiguous annuli of each pair and the same hydraulic diameter of passages between the fins in these passages. For the same reason the fins are

preferably radially opposite each other in pairs, with the fins in passage 15, for example, having the same spacing on a circumference medially of wall 12 as the fins in passage 16, and the fins in passages 15A, 15B spaced radially opposite fins in passage 15, 16A and 16B respectively. The rate of heat transfer is inversely proportional to the two-tenths power of the hydraulic diameter.

Viewed in another light, Figures 3 and 4 may be considered to illustrate the space between walls such as 11 and 13, 14 and 13A etc. divided into the two contiguous passages 15, 16 by a double comb-like annular member 40 of which wall 12 is a part. The fins 41 in passage 16 are of greater length than the fins 42 in passage 15 and the member 40 is positioned off center in the space between walls 11 and 13 so that the overall area (A) of passage 16 is greater than that (A²) for passage 15 in order to maintain the same ratio between the area A of passage 16 and its periphery 43, 45, 47, 49 (Fig. 4) as between the smaller area A² of passage 15 and the smaller periphery 44, 46, 48 in such manner as to preserve the ratio:

$$25 \quad \frac{4A}{(43)+(45)+(47)+(49)} = \frac{4A^2}{(44)+(46)+(48)+(50)}$$

Thus, wall 12, for example is not midway between walls 11 and 13 inasmuch as to preserve the ratios desired the fins 41 are not only longer than fins 42 but their distal ends are spaced further (at 51) from the opposite wall 13 of the passage 16 in which they are located than the fins 42 are (at 52) from wall 11 of passage 15. It is therefore evident that by equalizing flow areas in contiguous pairs of annulae the two heat exchange cycles between nitrogen and air in these passages are equal, whereas if the streams were to occupy entire concentric annulae of equal width the two cycles would not be equal because the areas and perimeters would not produce "equivalent diameters." For passage 15, 16 the heat loss from the outside through insulation (not shown) has the same effect on temperature of nitrogen and air in both cycles since both of these gases contact the same portion of outside shell 11 in both cycles.

In Fig. 5 the fins 53 in passage 16 are staggered with respect to the fins 54 in passage 15 so as to increase the elastic stability of wall 12 under high pressure.

There is complete balance of the heat transfer relation of the several fluids because the streams of nitrogen and air, respectively, are always in passages of equivalent diameter at opposite sides of an intervening wall 12, 12A etc. while the oxygen flowing through the channels 11, 11A always has a stream of air at one side and of nitrogen at the other. In Fig. 2 the air is in the passage 15A inwardly of the channel 17 through which the oxygen flows and the nitrogen is in the outer passage section 16. The relation is reversed in the following cycle where the nitrogen is in the inner passage 15A and the air is in the outer passage 16. When the air is caused to flow through channels previously filled with nitrogen and vice versa, the respective positions of these fluids with respect to oxygen are changed but the heat transfer relationships remain the same. With apparatus having several groups of passages each of which comprises 3 passages as in Figures 2 and 3, the streams of oxygen in both cycles are between a stream of nitrogen and a stream of air regardless of which of the latter is on the inner or outer side of the oxygen and the slight

differences of temperature between the nitrogen and air streams does not materially alter the heat transfer relationship because of the much smaller amount of oxygen. Although air in the outside annular passage 15 and nitrogen in the inner passage 16A (Figure 2) sweep in one cycle against walls 11 and 13A respectively which are not heat transfer surfaces, the air and gas streams are in reversed relation in the second cycle and any discrepancy in heat transfer efficiency is so slight, for all practical purposes, that it is inconsequential. Moreover, when several heat exchangers, even those having only one group of three passages as in Fig. 1, are employed in parallel or series connection in the manner disclosed in applicants' co-pending application 643,331 all minor differences due to the relationship of the nitrogen and air to the oxygen streams or to non-heat transferring walls are balanced out between two pieces of apparatus so that the heat exchange relationships become uniform.

With supply and discharge piping connected as indicated in Fig. 5, all of the valves 50 to 53 are open when air flows through the passage sections 15, 15A, Fig. 2 (and also 15B, Fig. 3) in the first cycle and nitrogen flows through the sections 16, 16A, 16B while all the valves 55 to 58 are closed. Conversely, in the second cycle all of the valves 55 to 58 are open when the nitrogen is to flow through the annular sections 16, 16A, 16B. The relative counter current relation of the flow of air to nitrogen and oxygen is maintained in both cycles as the directions of flow are not changed.

The invention described above embodies the generic principle of cooling (or heating) one fluid by means of two others while providing for transposing all the relations of the treated fluid and one of the treating fluids due to the requirements of a process. Likewise, it is possible to preserve the same heat exchange relationship among the fluids passing through the heat exchanger and maintain the same pressure drop through the various passages in each cycle of operation.

What we claim is:

1. In a heat exchanger for gaseous media;

means forming a pair of contiguous, concentric passages including a common intervening wall provided with radial fins extending into both passages to points short of the opposite walls bounding the latter with the fins in the inner passage that has the smaller radius being of greater length and having their distal ends further from the opposite wall of said passage than the corresponding fins in the outer passage of larger radius so as to maintain the same ratio of flow area to gas swept surface in the inner passage as in the outer.

2. In a heat exchanger for gaseous media; means forming a pair of contiguous parallel passages including a non-centrally located common intervening wall provided with fins extending into both passages to points short of the opposite walls bounding the latter with the fins in the passage that has the greater width being of greater length and having their distal ends located further from the opposite wall of said passage than corresponding fins in the adjacent passage of narrower width so as to maintain the same ratio of flow area to gas swept surface in both passages.

SVEN HOLM,
PER HILMER KARLSSON.
